UNITED STATES PATENT OFFICE

103,304

DESIGN FOR A SCREW

Frank K. Brown, South Dartmouth, Mass., assignor to Continental Screw Company, New Bedford, Mass., a corporation of Massachusetts

Application December 22, 1936, Serial No. 66,687

Term of patent 14 years

To all whom it may concern:

Be it known that I, Frank K. Brown, a citizen of the United States and a resident of South Dartmouth, county of Bristol, and State of Massachusetts, have invented a new, original, and ornamental Design for a Screw, of which the following is a specification, reference being made to the accompanying drawing, forming part thereof.

Fig. 1 is a plan view of a screw showing my new design; and

Fig. 2 is a perspective view of the same.

I claim:

The ornamental design for a screw, as shown.

FRANK K. BROWN.
